UNITED STATES PATENT OFFICE.

WILLIAM H. LOUNSBURY, OF OWEGO, NEW YORK.

IMPROVEMENT IN LASTS AND STANDARDS.

Specification forming part of Letters Patent No. 222,516, dated December 9, 1879; application filed May 31, 1879.

To all whom it may concern:

Be it known that I, WILLIAM H. LOUNSBURY, of Owego, in the county of Tioga and State of New York, have invented certain new and useful Improvements in Lasts and Standards; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

The nature of my invention consists in an improved iron last and standard, substantially as hereinafter set forth and claimed.

The object is to facilitate the repairing of boots and shoes.

In the drawings, Figures 1 and 2 are side elevations, partly in section, showing, respectively, the heel and toe portions of the standard. Fig. 3 is a section illustrating the application of the peg-float. Figs. 4 and 5 are bottom views of the heel and toe portions of the standard.

The heel-piece A is made separate from the standard and body of the last. The toe-piece B is also made separate. Both of these pieces have shanks whereby they can be set into the upper end of the standard. This standard has an opening, E, corresponding in shape to the shanks of the parts A B, and also a smaller recess, e, which is of use when a peg-float is to be used, the said latter implement being adjusted therein. The standard has a base, d, so that it will stand firmly upon the floor.

It will be seen that the toe-piece B, which also includes the sole or body of the last, has an incline when set in position, as in Fig. 1,

whereby, during the process of repairing either a boot or shoe, said articles will be effectively maintained in position upon said sole or toe-piece.

The heel-piece has a projecting edge fitting closely to the bottom of the heel, so as to receive the nails when driven through. The lasts of heel and sole parts are separate from each other, and are to be used separately on the standard, so that the boot or shoe can be taken off more easily than if they were connected.

The base d, above referred to, serves as a lap-iron to hammer leather on, the standard, in such case, being inverted and placed between the shoemaker's legs.

Suitable means may be provided for fastening the standard to a bench—as, for instance, screws through holes in the base.

What I claim is—

1. In a device for repairing boots and shoes, a standard provided with a socket, e, adapted to receive a peg-float, the said socket being enlarged at e for the insertion of the shanks or pins of the heel and sole pieces A B, as shown and specified.

2. A device for repairing boots and shoes, comprising a standard formed with a recess, e, a heel-piece, A, and a sole-piece, B, both of the said pieces being provided with a shank or pin adapted to fit into said recess e, as shown and specified.

In testimony that I claim the foregoing as my own I have hereto affixed my signature in presence of two witnesses.

WM. H. LOUNSBURY.
